UNITED STATES PATENT OFFICE.

WILLIAM A. BROWN, OF EVANSVILLE, INDIANA.

COLLAR WITH TIE-SLIDE.

1,132,555.

Specification of Letters Patent. Patented Mar. 23, 1915.

Application filed June 1, 1914. Serial No. 842,151.

To all whom it may concern:

Be it known that I, WILLIAM A. BROWN, a citizen of the United States, residing at Evansville, in the county of Vanderburg 5 and State of Indiana, have invented certain new and useful Improvements in Collars with Tie-Slides, of which the following is a specification.

The present invention relates to certain 10 new and useful improvements in collars, and has for its object to provide a turn down collar which embodies novel features of construction whereby the tie is held out of engagement with the collar-button so as to 15 slide freely back and forth, and is at the same time supported in position within the collar so that it can not work its way downwardly below the edge of the collar.

A further object of the invention is to 20 provide a turn down collar with a tie slide which can be manufactured at substantially the same cost as the ordinary turn down collar, which can be laundered without additional expense or any danger of being torn 25 and mutilated and which admits of the tie being readily placed in position within the collar and drawn freely back and forth therein as desired.

With these and other objects in view, the 30 invention consists in certain novel combinations and arrangements of the parts as will more fully appear as the description proceeds, the novel features thereof being pointed out in the appended claim.

For a full understanding of the invention, reference is to be had to the following description and accompanying drawing, in which:

Figure 1 is a plan view of the collar before the various flaps thereof are folded into position. Fig. 2 is a similar view with the tie slide flap folded upwardly. Fig. 3 is a similar view with the tie slide flap folded upwardly and the body of the collar folded 45 downwardly. Fig. 4 is a vertical sectional view through a collar showing the same as applied to the neckband of a shirt and also showing the tie in position therein.

Corresponding and like parts are referred 50 to in the following description and indicated in all the views of the drawing by the same reference characters.

Specifically describing the present embodiment of the invention, the numeral 1 55 designates the body of the collar which is adapted to be applied to the neckband 2 of

a shirt in the usual manner and is provided at opposite ends thereof with the tongues 3. A button-hole 4 is provided in the body 1 at substantially the central portion thereof 60 and toward its lower edge, and corresponding button-holes 5 are also formed in the tongues 3. The button-hole 4 is adapted to engage the collar-button 6 at the back of the neckband of the shirt, while the button-holes 65 5 are adapted to engage the collar-button 7 at the front of the neckband of the shirt, the two tongues 3 then overlapping each other.

The turn down flap 8 extends substantially the full length of the body portion 1 70 along one side thereof, while the tie slide flap 9 extends along the edge of the turn down flap 8 terminating somewhat short of the ends of the former, although being of a sufficient length to extend around the back 75 and sides of the collar. This tie slide flap 9 is uniform in width throughout its entire length and has the rounded corners 9^a so as to avoid all sharp projections. The width of the tie slide flap 9 is considerably less 80 than that of the turn down flap 8, but is sufficient to extend upwardly above the button-hole 4 when the flaps are folded into operative position, as indicated by Fig. 3.

The necktie 10 is adapted to be inserted in 85 the space between the turn down flap 8 and the tie slide flap 9, and the latter serves both to hold the necktie out of engagement with the rear collar-button 6, and also to support the lower edge of the necktie so that the latter is prevented from working downwardly a sufficient amount to be exposed below the edge of the collar. It will thus be obvious that the tie can slide freely back and forth between the flaps 8 and 9 without catching 90 upon or engaging the collar-button 6, and that it is at the same time supported in proper position. By extending the tie slide flap 9 throughout the greater portion of the length of the flap 8 and making it of a uniform width, a collar is provided which can be readily laundered without the exercise of unusual care and with the usual machinery, and which has no small tabs or angular projections adapted to be torn and mutilated. 95

Having thus described the invention, what I claim as new and desire to secure by Letters Patent, is:—

The herein described collar including a body portion having a button-hole therein, 100 a turn down flap, and a tie slide flap extending continuously throughout the greater

portion of the length of the turn down flap so as to extend around the back and sides of the collar when in use, said tie slide flap being of a uniform width throughout its 5 length and being adapted to be folded upwardly between the body and turn down flap so as to extend above the button-hole of the body and provide a substantially continuous support for the lower edge of the tie as well

as keep the tie out of engagement with the 10 collar-button entering the button-hole of the body.

In testimony whereof I affix my signature in presence of two witnesses.

WILLIAM A. BROWN.
